UNITED STATES PATENT OFFICE

FREDRIK CARLSTEDT, OF STOCKHOLM, SWEDEN, ASSIGNOR TO ELECTROLUX CORPORATION, OF DOVER, DELAWARE, A CORPORATION OF DELAWARE

VACUUM CLEANER

Application filed December 29, 1931, Serial No. 583,670, and in Germany December 18, 1930.

My invention relates to vacuum cleaners and more particularly to the combination with a vacuum cleaner unit of a flexible hose for connecting the suction or blowing tools with the vacuum cleaner unit.

When a hose is interposed between the suction nozzle of a vacuum cleaner and the fan, the resistance of the hose is a factor of importance. The resistance decreases rapidly with increase in diameter of hose. On the other hand, increase in diameter means increase in weight to the operator who holds a part of the hose or one end thereof in the hand. It is the principal object of this invention to obtain an appreciable decrease in resistance to flow without increasing the weight in the hand of the operator or, alternatively, decreasing the weight in the hand of the operator without increasing the resistance to flow in the hose.

The nature and advantages of the invention will be pointed out as the description proceeds, taken in connection with the accompanying drawing, in which a flexible hose is shown, connecting a suction tool with a vacuum cleaner unit and which drawing forms a part of this specification.

In the drawing:

Fig. 1 is an assembly view showing the vacuum cleaner unit with the hose attached thereto; and

Fig. 2 shows a detail.

In the following description and in the claims, parts will be identified by specific names for convenience but they are intended to be as generic in their application to similar parts as the art will permit.

In the drawing, 10 denotes a suction cleaner unit of known kind comprising a casing enclosing a dust bag 20 and a fan 21 driven by an electrically operated motor 22. The ends of the cleaner casing are covered by caps 11 and 12, respectively, in which caps the suction and blowing openings 13 and 14 respectively are arranged. Said openings 13 and 14 are adapted to receive a coupling member 17, as shown more in detail in Fig. 2. The coupling member 17 is threaded at 24 to fit into the inlet opening 13. The coupling member is internally threaded at 25 to permit a ro-

tatable member 26 to be screwed thereinto. Member 26 is a part of the hose generally designated by reference character 15. Member 26 is rotatably mounted on a rigid sleeve or end member 27 which is secured to the cone-shaped flexible hose member 30. A packing 28 is provided in a recess between members 26 and 27.

To the other end of the flexible hose member or section 30 is attached a rigid member 31 which is adapted to fit into a tubular member 19 in turn connected to a suction nozzle 16. The parts are in general circular as shown and the flexible hose member 30 is of gradually increasing diameter, internally and externally, from the end attached to member 31 to the end attached to member 27. As shown in the drawing, the hose may be of so-called "spiral" construction.

In operation, the cleaner unit rests on the floor or carpet. The operator lifts the part 31 and holds either this or some adjacent part in the hand. Consequently, the part of the flexible hose which is nearer to the cleaner unit 10 rests on the floor, whereas the part nearer to member 31 is lifted by the operator. It will thus be seen that the part nearer the cleaner unit which rests on the floor is the heavier part and the part of larger cross-sectional area, while the part adjacent the member 31 is appreciably lighter. If the hose were of uniform diameter equal to the diameter adjacent the part 31, the resistance would be high compared with the hose as shown and described.

In the designing of vacuum cleaners, an important requirement is to keep the resistance to flow of air through the apparatus itself and the implements connected therewith as low as possible. Due to this fact, it is desirable to give the suction or blowing conduit a large inner cross section. The use of such heavy conduits is, however, disadvantageous, especially in vacuum cleaners of the domestic type, as that end of the conduit, to which the tools are connected, can be manipulated only with great difficulty, due to the large dimensions of the conduit.

This disadvantage is overcome by the present invention, without the requirement of low

resistance to flow in the conduit being dispensed with, as the effective section of flow of the flexible hose is the inner cross section midway between the ends thereof, provided that the increase in inner cross section is practically uniform, as is the case in the embodiment shown in the drawing.

The invention further provides the advantage that, in the suction operation, thread, 10 cotton-waste and the like will not stick in the hose as this increases in the direction of flow of air. This last mentioned advantage is particularly important in spiral hoses.

It will be obvious that changes in construction may be made without departing from the spirit and scope of the invention. In the specific type of cleaner shown, the vacuum cleaner unit is adapted to be pulled on the floor or carpet by pulling on the hose. Obviously, the 20 part 19 may be omitted and the suction tool connected directly to the member 31, or the member 31 may itself constitute the nozzle, as is known in cleaners of this type. It is to be understood that the invention is not limited to the specific type of vacuum cleaner 25 shown and described.

What I claim is:

1. The combination with a vacuum cleaner unit including a casing having a suction inlet 30 adjacent the floor, of a hose adapted to be held in the hand at one end and secured to said inlet at the other end and of such length as to have a portion thereof resting on the floor when an end is held in the hand comprising 35 a flexible section of varying internal and external diameter to provide varying cross-sectional area and varying weight per unit length, the smallest cross-sectional area being at the end to be held in the hand and 40 the largest cross-sectional area being at the end adapted to be attached to said suction inlet, whereby the end to be held in the hand is relatively light and the part resting on the floor is relatively heavy and the cross-sectional area increases in the direction of air 45 flow with the hose connected to the suction inlet, and a suction tool adapted to be connected with the end of the hose of small diameter.

2. The combination with a movably mounted vacuum cleaner unit including a casing having a suction inlet adjacent the floor, of a hose adapted to be held in the hand at one end, said hose serving to conduct air to the 55 vacuum cleaner unit and for pulling the unit on a floor or other surface, a rotary connection between said hose and said inlet at the other end and said hose being of such length as to have a portion thereof resting on the 60 floor when an end is held in the hand and comprising a flexible section of varying internal and external diameter to provide a varying cross-sectional area and varying weight per unit length, the smallest cross-sectional area being at the end to be held in the hand and the

and the largest cross-sectional area being at the end adapted to be attached to said suction inlet, whereby the end to be held in the hand is relatively light and the part resting on the floor is relatively heavy and the cross-sectional area increases in the direction of air flow with the hose connected to the suction inlet, and a suction tool adapted to be connected with the end of the hose of lesser diameter.

3. In apparatus of the character set forth, a vacuum cleaner unit having an inlet opening, a suction nozzle, and a hose comprising a rigid end member adapted to be connected to said nozzle and comprising a flexible hose section attached to said end member and having a gradually increasing internal diameter away from said rigid end member and a similarly increasing external diameter and comprising a connection member attached to the large diameter end of the hose section and adapted to be connected to said inlet opening.

4. The combination with a movably mounted vacuum cleaner unit including a casing having a suction inlet adjacent the floor, of a hose adapted to be held in the hand at one end and secured to said inlet at the other end, said hose serving to conduct air to the vacuum cleaner unit and for pulling the unit on a floor or other surface and being of such length as to have a portion thereof resting on the floor when an end is held in the hand, said hose comprising a flexible section of varying internal and external diameter to provide varying cross-sectional area and varying weight per unit length, the smallest cross-sectional area being at the end to be held in the hand and the largest cross-sectional area being at the end nearer the suction inlet, whereby the end to be held in the hand is relatively light and the part resting on the floor is relatively heavy and the cross-sectional area increases in the direction of air flow with the hose connected to the suction inlet and the center of gravity is nearer the unit, relative to a hose of uniform diameter, and a suction tool adapted to be connected to the end of the hose of smaller diameter.

5. The combination with a vacuum cleaner unit including a casing having a suction inlet, and a suction nozzle, of a hose adapted to be held in the hand and connected to the suction nozzle at one end and connected to said suction inlet at the other end, said hose serving to conduct air to the vacuum cleaner unit and being of such length as to have a portion thereof resting on the floor when an end is held in the hand, said hose comprising rigid portions and a flexible section of varying internal and external diameter connected between said rigid portions to provide varying cross-sectional area and varying weight per unit length, the smallest cross-sectional area being at the end to be held in the hand and the

largest cross-sectional area being at the end nearer the suction inlet, whereby the end to be held in the hand is relatively light and the part resting on the floor is relatively heavy 5 and the cross-sectional area increases in the direction of air flow with the hose connected to the suction inlet and the center of gravity is nearer the unit, relative to a hose of uniform diameter.

10 In testimony whereof I have affixed my signature.
